(57) **CLAIM**

The ornamental design for a nectar bottle for a bird feeder, as shown and described.

DESCRIPTION

FIG. 1 is a front perspective view of an embodiment of a nectar bottle for a bird feeder embodying my new design.

FIG. 2 is a left side view thereof.

FIG. 3 is a right side view thereof.

FIG. 4 is a top view thereof; and,

FIG. 5 is a bottom view thereof.
